UNITED STATES PATENT OFFICE.

DAVID STOLL, OF BROOKLYN, NEW YORK.

DESIGN FOR METAL SHEET OR SIMILAR ARTICLE OF MANUFACTURE.

Application filed August 15, 1924. Serial No. 10,463. Term of patent 7 years.

To all whom it may concern:

Be it known that I, DAVID STOLL, a citizen of the United States, residing at the city of New York, borough of Brooklyn, county of Kings, and State of New York, have invented a new, original, and ornamental Design for Metal Sheet or Similar Article of Manufacture, of which the following is a specification, reference being had to the accompanying drawing, forming part thereof.

The figure is a top plan view of a piece of sheet metal or similar article of manufacture embodying my new design.

Sheet metal embodying my new design is made and sold as a separate article of manufacture. It is intended that sheet metal with my new design impressed therein be used in the manufacture of silver hollowware and similar articles.

I claim:

The ornamental design for metal sheet or similar article of manufacture as shown and described.

DAVID STOLL.
